UNITED STATES PATENT OFFICE

JAMES SHIELDS THOMPSON, OF PELHAM, NEW YORK

BRAKE-SHOE.

1,130,680:

Specification of Letters Patent.

Patented Mar. 2, 1915.

Application filed June 17, 1914. Serial No. 845,538.

To all whom it may concern:

Be it known that I, JAMES S. THOMPSON, a citizen of the United States, and a resident of Pelham, in the county of Westchester and 5 State of New York, have made and invented certain new and useful Improvements in Brake-Shoes, of which the following is a specification.

My invention relates to an improvement 10 in brake shoes, and more particularly to such as have the wearing face of somewhat greater length than the back of the shoe, the ends being prolonged and chilled in such a way as to afford a constantly and practi- 15 cally uniform wearing surface throughout the life of the shoe, that portion of the wearing face between the chilled ends being of soft cast iron, the prolongations on the ends of the shoe affording a place for chill- 20 ing without hardening any portion between the ends. This form of shoe has heretofore met with several objections, the principal one being that the chilled metal, being extremely brittle, is apt to break away or part 25 from the unchilled portion.

The object of my invention is to overcome this objection, and to so construct the shoe that the chilled ends will be firmly bound or bonded to the unchilled body portion, and 30 thereby to secure to the shoe all the advantages arising from an unchilled cast iron shoe having chilled ends, and with this and other ends in view, the invention consists in certain novel features of construction and 35 combinations of parts as will be hereinafter fully described and pointed out in the claims.

In the accompanying drawings, Figure 1 is a plan view of a shoe constructed in accordance with my invention. Fig. 2 is a 40 view in side elevation, one end thereof being shown in section in order to show the bonding material embedded partly in the ends, and partly in the body, of the shoe. Fig. 3 is a bottom plan view of the shoe. Fig. 4 is a 45 sectional view taken through the line 4—4 of Fig. 2; and Fig. 5 a similar view taken on the line 5—5 of Fig. 2 looking in the direction as indicated by the arrow.

Referring to the drawings, it will be seen 50 that the body 6 of the shoe is somewhat longer on its wearing face 7 than on the back 8, the ends 9 of the shoe being somewhat prolonged for the purpose of lending to the shoe the usual area or surface of un-

chilled cast iron with the additional area or 55 surface of chilled metal.

Into the mold in which the shoe is cast, and in the ends thereof, I place a plurality of layers, or a bundle of expanded metal, wire mesh, or other binding, bonding or re-inforcing reticulated metal 10, and of such width as to extend practically across the body of the shoe, and in length to extend from that portion 11 of the end which is chilled into the body 6 of unchilled metal, 60 the idea being to have this bonding or binding reticulated metal 10 to extend from the chilled into the unchilled portions of the shoe, to avoid the danger of the two metals cracking and separating. I have learned 65 from experience, however, that it is desirable, if not absolutely essential, to first treat the reinforcement or bonding metal 10 with a heat resisting material, such, for instance, as is described in the patents granted to 70 Wesley G. Nichols, Nos. 938,688 and 938,689, and dated November 2, 1909, for otherwise the metal constituting the ends 11 of the shoe, and in contact with which the chilling blocks are placed, cools or chills so rapidly, 75 by reason of the chilling blocks and the cold metal constituting the bonding material 10, as to leave spaces between the latter and said chilled metal, while that portion of the insert which extends into the unchilled portion 6 is burned or destroyed, causing the 80 formation of blow-holes and resulting in an impractical or worthless shoe. By first 85 treating, however, the insert of reticulated metal with a heat resisting material, this objection is overcome, the chilled metal completely surrounding and embedding the insert, while that portion of the latter extending into the unchilled portion of the metal 90 remains intact, thereby forming a strong 95 bond between the chilled and unchilled portions of the shoe. While I have shown and described several layers of this mesh or expanded metal embedded in the end of the shoe, I of course do not limit myself to the 100 particular form or kind of mesh, nor to the quantity or manner of distribution of the same, so long as such is completely embedded in both the chilled and unchilled portions of the metal. Nor do I limit my 105 claims to the particular way or manner, or to the extent of chilling the ends of the shoe, as the chilling blocks, larger or smaller in size,

may be placed upon the ends of the shoe, or upon the back of the shoe adjacent the ends, as desired, it being necessary only to fulfil the requirements of this invention, to chill 5 the prolonged ends of the shoe, and to bind the same with the unchilled portions.

Therefore: what I claim is:—

1. A brake shoe comprising a body portion of unchilled metal and provided with 10 prolonged ends of chilled metal, and a reticulated metal insert embedded in the prolonged chilled ends and extending a short distance into the unchilled metal of the body whereby to tie or bind the chilled and 15 unchilled metals together.

2. A brake shoe comprising a body portion of unchilled metal and having prolonged ends of chilled metal, and an insert of expanded metal embedded in the prolonged chilled ends and extending a short 20

distance into the unchilled metal of the body whereby to securely bind or tie the prolonged chilled ends onto the unchilled body.

3. A brake shoe comprising a body of unchilled metal, and provided with chilled ends, and a metal insert covered with a heat resisting material embedded in the chilled ends and extending into the unchilled metal of the body. 25 30

Signed at New York, borough of Manhattan, in the county of New York and State of New York, this 8th day of June, A. D. 1914.

JAMES SHIELDS THOMPSON.
